(57) **CLAIM**

The ornamental design for a bath fan with speaker, as shown and described.

DESCRIPTION

FIG. 1 is a first perspective view of a bath fan with speaker showing our new design;

FIG. 2 is a front view thereof;

FIG. 3 is a right side view thereof;

FIG. 4 is a left side view thereof;

FIG. 5 is a rear view thereof;

FIG. 6 is a plan view thereof; and,

FIG. 7 is a second perspective view thereof, shown in a position of use with unclaimed environmental subject matter. The broken lines immediately adjacent to the shaded area represent unclaimed boundaries of the design. The broken lines showing the remainder of the bath fan with speaker are for environmental purposes only and form no part of the claimed design.
